UNITED STATES PATENT OFFICE.

JOHNATHAN D. POWELL, OF IMLAY CITY, MICHIGAN.

SILo.

No. 817,986.

Specification of Letters Patent.

Patented April 17, 1906.

Application filed June 14, 1905. Serial No. 265,211.

To all whom it may concern:

Be it known that I, JOHNATHAN D. POWELL, a citizen of the United States, residing at Imlay City, in the county of Lapeer and State of Michigan, have invented a new and useful Silo, of which the following is a specification.

This invention relates to silos; and a special object of the invention is to provide an improved door which shall be capable of being conveniently opened and closed against the pressure of the contents of the silo, so as to permit the latter to be gradually removed.

Further objects of the invention are to simplify and improve the construction and operation of this class of devices.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that the right is reserved to any changes, alterations, and modifications to which recourse may be had within the scope of the invention and without departing from the spirit or sacrificing the efficiency of the same.

In said drawings, Figure 1 is a front elevation of a portion of a silo constructed in accordance with the principles of the invention. Fig. 2 is a horizontal sectional view taken on the plane indicated by the line 2 2 in Fig. 1.

Fig. 3 is a vertical sectional detail view taken on the plane indicated by the line 3 3 in Fig. 1. Fig. 4 is a perspective detail view showing parts of the door-fastening means detached. Fig. 5 is a perspective detail view of a wedge used in connection with the invention. Fig. 6 is a sectional detail view taken on the plane indicated by the line 6 6 in Fig. 1.

Corresponding parts in the several figures are indicated throughout by similar characters of reference.

In Figs. 1 and 2 of the drawings has been shown a portion of a silo of ordinary construction, the same being composed of a plurality of staves 1 1, which are preferably grooved and tongued, as at 2 3, in order that the said staves may be perfectly

matched and tight joints secured. The staves are connected together to form a cylindrical structure of suitable dimensions, said staves being bound by means of hoops 4, or rods 4, the ends of which are connected together by means which will be presently described. A door-opening is formed in the silo by omitting two or more staves, the staves adjacent to said opening, which have been specially designated 5 and 5', while not necessarily differing from the remainder of the staves may be described as constituting the door-posts, the same extending from the top to the bottom of the silo.

The door is made up of a plurality of sections S, each of suitable height to be conveniently manipulated—say about three feet. Each of these door-sections is composed of two leaves or folding members 6 6', preferably having groove-and-tongue connection with the door-posts, with which latter they are also connected by means of leaf-hinges H, the inner leaves of which, 7, are provided with slots 8 for the reception of the screws or other fastening members 9, whereby they are connected with the door-members, which latter, it will thus be seen, have a limited sliding movement with relation to the hinges and to the staves which constitute the door-posts. The several door-sections S have their ends abutting upon each other, so that any one of said door-sections may be opened independently of the rest.

The hoops or rods 4, whereby the staves constituting the silo and the doors of the same are bound together, are located in the planes of the abutting ends of the door-sections, and their terminals are threaded, as shown at 9', and extended through perforations in the outer arms of U-shaped bracket-clips 10, which are preferably disposed in contact with the outer sides of the staves 5 and 5', constituting the door-posts. The inner brackets of the clips 10 are provided with perforations 11 for the reception of hooks 12, formed at the ends of connecting-bars 13, of round iron, which latter extend across the abutting ends of the door-sections. When these connecting members are in position, the nuts 14 may be tightened upon the threaded ends 9' of the hoops or rods 4, thus tightening the latter upon the structure forming the silo. It will be observed that prior to this tightening all or nearly all of the door-sections should be placed in position.

The inner edges of the members 6 and 6' of

the door-sections are beveled upon their inner and outer sides, as shown at 15, 16, reinforcing-strips 22 being placed upon the outside. A binding-strip 17 of trapezoidal or 5 approximately triangular or wedge-shaped cross-section is provided to engage the inner beveled portions 15. Said binding-strip is provided with perforations 18 for the reception of bolts 19, which also pass through perforations 20 in an exteriorly-disposed locking-strip 21, which is likewise trapezoidal or wedge-shaped in cross-section to engage the beveled portions 16 of the door members and the inner edges of the reinforcing-strips 22. 15 The binding-bolt 19 is provided with a wing-nut 23, adapted to bear against the locking-strip.

The upper and lower edges of the door-sections are beveled upon their inner sides, 20 shown at 24, to enable material, such as a portion of the ensilage, to be packed into the grooves thus formed to form absolutely tight joints. When the door-sections are placed in position, the free edges of said door-sections are brought nearly to a closed position and the binding-strip 16, bolt 19, and locking-strip 21 are then placed in position and the nut tightened, thus forcing the door members apart and into intimate contact 25 with the staves constituting the door-posts, while the free edges of the door members are intimately connected by the binding and locking strips. The slight sliding movement of the door members necessary to bring 30 about this adjustment is made possible by the presence of the slots 7 in the hinge-leaves 8. The doors are then further tightened by driving wedges, as 25, between the doors and the connecting members 13. To permit the 35 door-sections to be closed or opened, the connecting members 13 may be swung out of the path of said door-sections at the upper and lower ends of the latter, as indicated in Fig. 3 of the drawings, so that said door-sections 40 will be temporarily unobstructed. The binding-screws and the binding and locking strips, together with the wedges, constitute means whereby the doors may be readily forced 45 shut against the powerful pressure existing within the silo.

Having thus described the invention, what is claimed is—

1. A silo composed of matched staves two of which are spaced apart to constitute door-posts; and door-sections each composed of 55 two members hingedly and slidably supported with relation to the door-posts.

2. A silo composed of matched staves two of which are spaced apart to constitute door-posts; door-sections each composed of two members grooved and tongued to match the door-posts; and hinges having slotted leaves connecting said door members hingedly and slidably with the door-posts.

65 3. A silo having staves constituting door-

posts; and door-sections hingedly connected with said posts; in combination with means including binding-strips, locking-strips, and connecting-bolts for connecting together the free edges of the door members.

4. A silo-door comprising hingedly-supported members having free edges beveled upon their inner and outer sides and reinforcing-strips upon their outer sides; in combination with binding and locking strips of trapezoidal cross-section having registering apertures, and a connecting-bolt having a wing-nut.

5. A silo-door comprising hingedly-supported members having free edges beveled upon their inner and outer sides; in combination with binding and locking strips engaging said inner and outer beveled sides, reinforcing-strips for the latter, and connecting-bolts and wing-nuts.

6. A silo having a door composed of a plurality of sections abutting upon one another, means for hingedly connecting the members of said door-sections with the staves of the silo constituting the door-posts, means for connecting the free edges of the members of the door-sections, U-shaped clamps disposed adjacent to the abutting ends of the door-sections, connecting-bars having hooks connected pivotally with the inner arms of said U-shaped clamps, and hoop-rods having threaded ends extending through apertures in the outer arms of the U-shaped clamps and provided with tightening-nuts.

7. In a silo having a door comprising a plurality of sections abutting upon one another, hoops or rods encircling the silo and including pivotally-supported connecting-bars disposed in alinement with the abutting ends of the door-sections.

8. In a silo, a door comprising a plurality of sections having beveled upper and lower edges abutting upon one another to form V-shaped packing-grooves.

9. In a silo, a door comprising a plurality of sections, hoops or rods encircling the silo and including pivotally-supported connecting members disposed in alinement with the door-sections, and wedges driven between said connecting members and the door-sections.

10. In a silo, a door comprising a plurality of sections each comprising a pair of hingedly-supported members beveled at their free edges, locking and binding strips engaging the free edges of the door members, tightening-bolts connecting said strips, hoops encircling the silo, and wedges driven between said hoops and the door members.

11. In a silo, a door comprising a plurality of hingedly and slidably supported sections, means for forcing the free edges of the door members comprising the several sections into alinement with each other and then apart, said means including wedge-strips and tight-

ening-bolts, and additional wedge means for forcing the members of the door-sections in an inward direction.

12. In a silo, a door including a plurality of sections each comprising a pair of members hingedly and slidably connected with adjacent staves of the silo constituting door-posts; in combination with means for drawing the free edges of the door members into registry with each other and then spreading said door members bodily apart from each other.

13. A silo composed of matched staves two of which are spaced apart to constitute door-posts, door members grooved and tongued to match said door-posts, means for

supporting said door members slidably with relation to the door-posts, and means for forcing the free edges of the door members into registry with each other and then spreading said door members bodily and forcibly apart and into intimate contact with the edges of the staves constituting the door members.

In testimony that I claim the foregoing as my own I have hereto affixed my signature in the presence of two witnesses.

JOHNATHAN D. POWELL.
